UNITED STATES PATENT OFFICE.

EMILE KINST, OF CHICAGO, ILLINOIS.

BALL-BAT.

SPECIFICATION forming part of Letters Patent No. 430,388, dated June 17, 1890.

Application filed April 22, 1890. Serial No. 348,981. (No model.)

To all whom it may concern:

Be it known that I, EMILE KINST, a citizen of the United States, residing at Chicago, in the county of Cook and State of Illinois, have 5 invented certain new and useful Improvements in Ball-Bats, which are fully set forth in the following specification, reference being had to the accompanying drawing, forming a part hereof.

10 The drawing shows my improved ball-bat in side elevation, thus showing all its essential and novel features. The front or rear view of this bat shown in a drawing would show nothing which differed in outline from 15 an ordinary ball-bat, the sides of this my bat being straight and converging from the outer or top end to the handle in just the same way as the sides of the present well-known form of ball-bat converge. I mean more particularly 20 those bats known as "base-ball bats."

The object of my invention is to provide a ball-bat which shall produce a rotary or spinning motion of the ball in its flight to a higher degree than is possible with any present 25 known form of ball-bat, and thus to make it more difficult to catch the ball, or, if caught, to hold it, and thus further to modify the conditions of the game, as will presently be shown; and to attain said ends I construct 30 my new ball-bat in substantially the following manner, namely:

I construct a ball-bat—if, for instance, it is to be used in playing base-ball—in every essential feature just like the present well-known form of bat, and then by bending change 35 its permanent form into that substantially as shown in the drawing, so that the longitudinal axis of the bat shall lie in a plane from the points 0 to 1 with a receding curve, (the 40 face toward the reference-figure of the drawing being the front or face of the bat,) which gradually reverses from the point 1, and at the points 2, 3, and 4 has its radial central point or points on the face side of the bat in 45 form and relative proportions, substantially as shown.

The smaller part of the bat from the point marked 0 is the handle, and from said point up to the upper end of the bat, constituting 50 about or a little more than one-third of the entire length of the bat, is the striking part.

In use the following results are obtained with my bat, namely: When a ball is struck with that part of the bat comprised between the points 0 and 1, the ball will receive, in addition to the flight produced by the blow, a rotary motion, more or less violent in proportion as it happens to hit the bat near the point 1 or 0. This motion will of course be in the same direction as if the ball had been rolled on the face of the bat from the point 0 toward the upper end of the bat, and on account of the manner in which bats are usually held at the moment they hit the ball—a little back of or pointing backward from the striker—this 65 said rotation will be given to the ball at the point 2 and beyond it, but with decreasing force, until near or at the point 3, where for a short distance on either side of it there will be a neutral point—that is, its shape will not, on account of the form and position already explained, tend to give the ball any more of a rotary motion than a straight bat would do. Beyond said neutral space toward the point 4 and on either side of it the ball receives a rotary or spinning motion contrary to that given 70 from or between the points 0 and 3. In addition to the said special results, there are several others attained by the use of my new bat—as, for instance, when the ball strikes the bat between the points 0 and 3 it will not fly straight from the bat—that is, in a line normal or vertical to the axial line of the handle of the bat—but it will rise upward, and when the ball is caught in flying from such a 75 blow it will be very difficult to retain it in the hand on account of the said rotary or spinning motion imparted to it. If the ball is struck with the upper end of the bat, its tendency will be to seek the ground directly and to roll from the striker and to stay on or near the ground. With these said results, owing to the peculiar form of my bat, the game becomes more difficult to play, and therefore much more interesting and exciting, because 80 the innings will not be so easily attained, and consequently the time of the game will also be shortened, and on account of the said spinning motion given to the ball by my bat it will 85 also be sent farther across the field.

100 While the cross-section of my ball-bat may be circular like any other bat, it may also be

varied, so as to be more or less oval-round at places, as between the points 1 and 2.

What I claim is—

1. A ball-bat wherein the longitudinal axis of the striking part is bent into a series of curves which lie in the same plane, substantially as specified.
2. A ball-bat wherein the longitudinal axis

of the striking part is bent into a series of curves from the point 0 through the points 1 2 3 4, substantially as specified.

EMILE KINST.
